JPO Design Division Prior Art Ref. No. HA15021476, disclosed on p. 122 of Goggle, vol. 11, dated Nov. 1, 2003, which is furnished in the National Center for Industrial Property Information on Sep. 25, 2003.

Primary Examiner—Ruth McInroy

(74) Attorney, Agent, or Firm—Karl G. Hanson

(57) **CLAIM**

The ornamental design for a side portion of a welding helmet, as shown and described.

DESCRIPTION

FIG. 1 is a perspective view, showing the new design for a side portion of a welding helmet;

FIG. 2 is a left side view, the right side view being a mirror image thereof;

FIG. 3 is a top view thereof;

FIG. 4 is a front view thereof;

FIG. 5 is a bottom view thereof; and,

FIG. 6 is a rear view thereof.

The broken lines form no part of the claimed design, and the shading is provided to illustrate contour only and is not an indication of texture, gloss, etc.

1 Claim, 4 Drawing Sheets
